UNITED STATES PATENT OFFICE.

OBBO B. BERG, OF ACKLEY, IOWA.

PLUMB-BOB.

1,178,835.

Specification of Letters Patent. Patented Apr. 11, 1916.

Application filed January 14, 1915. Serial No. 2,232.

To all whom it may concern:

Be it known that I, OBBO B. BERG, a citizen of the United States, residing at Ackley, in the county of Hardin and State of Iowa, have invented certain new and useful Improvements in Plumb-Bobs, of which the following is a specification.

This invention relates to plumb bobs, and has for an object to provide a marking pin 10 which is slidably associated with a housing or body, to permit indenting a surface with which the pointed end of the pin contacts, at the same time obviating possibility of distorting the pin by reason of the impact with 15 the surface which is to be marked.

Another object consists in the production of a plumb bob which is constructed of few, simple, and compact parts and which are so arranged, that the same may be dropped 20 from any distance and yet remain upright and in position to mark the required location.

With the above and other objects in view, my invention consists in the details of construction, combination and arrangement of parts as will be hereinafter more fully described and pointed out in the appended claims and illustrated in the accompanying drawings, in which;

30 Figure 1 is a side elevational view of a plumb bob constructed in accordance with my invention, illustrating the application of the invention, Fig. 2 is a longitudinal sectional view of the same, Fig. 3 is a perspective view of the pin used in the present invention, and Fig. 4 is a side elevational view of the bob, a portion thereof being broken away to disclose the pin.

Similar letters refer to similar parts 40 throughout the several views.

Referring to the drawings, numeral 1 designates the casing or body portion of my invention shown resting on the surface 13 to be marked and which is preferably of a 45 cylindrical configuration, formed of brass or other suitable material and provided with a central bore 2 extending longitudinally therethrough. A portion of the body 1, surrounding the bore 2 and adjacent thereto, is 50 cut out to provide an enlarged annular recess 3 at one end of the casing, the wall of which is threaded for engagement with the threaded annular flange of the cap member herein-after referred to. The shoulder provided 55 by this recess forms a seat or rest for the stop 4, which stop in the present instance

comprises a pin disposed within the recess and extending transversely of the bore 2. This pin 4 is primarily intended to pass through the slot of the marking pin described below and is held stationary within the recess so as to limit the reciprocable movement of the marking pin 5.

The member 5 comprises an elongated steel core or pin, terminating at one end in a point 6 which by its penetration of a surface, marks the spot to be found or located thereupon. The pin is further provided with an enlarged head 7, having a convex surface so as to conform to and be snugly engaged by the palm of the hand, when the latter is brought sharply in contact therewith, for exerting pressure upon the pin and causing the point to indent and mark the spot desired. Positioned a slight distance below the head 7 and passing transversely through the pin 5, is a slot 8 of a depth sufficient to permit of an appreciable reciprocatory movement of the marking pin within the bore 2 of the housing. A longitudinal opening 9 extends centrally through the head 7 and communicates with the slot 8, to permit the passage of a cord 10 therethrough, which cord is adapted to be secured to the stop or limiting pin 4.

A cap 11 having a knurled edge to facilitate adjustment, and provided with a central opening to permit movement of the pin 5 therethrough, is fitted to the housing 1 so as to retain the separate parts of the invention in assembled relation. It is provided with an annular depending projection 12, externally threaded and adapted to be inserted in the recess 3 for engagement with the threaded wall thereof. When the cap is thus in place, this projection abuts against the stop 4 and retains the same against displacement from the recess.

Thus, it will be noted that any upward pull exerted upon the cord 10, will be communicated directly to the pin 4, the cord 10 being attached thereto, and as the pin 4 is connected to the housing 1, by means of the cap 11, the housing will necessarily move upward with the cord. The marking pin 5, however, is not affected by any such pull and does not move with the housing until the stop 4, in its upward travel comes in contact with the upper terminus of the slot 8, at which time the pin 5 must necessarily be carried upward with the housing.

In operation, the housing 1 is suspended

by means of the cord 10, over the surface to be marked, in which position it will be understood that the pointed end 6 of the marking pin is depending externally of the 5 bore 2 and below the housing; the upper terminus of the slot 8, being in engagement with stop 4. Upon releasing the cord, the housing drops to the intended location, and the point 6, being in advance of the housing 10 contacts with the surface to be marked, and by weight of its fall, indents the spot to be located. Owing to the free, slideable movement of the pin 5 within the housing, the point 6 thereof is protected against injury 15 or distortion, to which it would undoubtedly be subjected, were it made integral with the housing. When dropped from a height the weight of the housing 1, combined with the flat surface which it presents to the subja- 20 cent surface will tend to hold the device in an upright position, so that to mark the spot thus located, it is but necessary to strike the palm of the hand against the enlarged head of the pin, to cause it to penetrate and 25 thus designate the required point.

What is claimed is:

1. A plumb bob, including a body, a cap for said body, a pin inserted through said cap and body and capable of free reciproca- 30 tory movement therethrough, and means as- sociated with said body for limiting the movement of the said pin.
2. A plumb bob, including a body, a pin, provided with a slot, and movable within 35 said body, and means associated with said body and extending through said slot for limiting the movement of the pin within said body.
3. A plumb bob, including a tubular body, 40 a cap for said body, an elongated pin mem- ber inserted through said cap and body and movable therethrough, said pin provided with a slotted upper end, and a stop as- 45 sociated with said body and extending through said slotted end for limiting the movement of the pin within said body.
4. A plumb bob, including a tubular body provided with a recess, an elongated marking pin disposed within said body and mov- 50 able therethrough, said marking pin pro- vided with a slot extending transversely therethrough, a stop seated in said recess and projecting through said slot to limit the

movement of said pin, and a cap threaded into said recess and engaging said stop 55 whereby the latter is held in secured position.

5. A plumb bob, including a housing hav- ing a central bore, a marking pin slideable through the bore and having a pointed end 60 for marking surfaces, a stop arranged in said housing and extending through said bore and marking pin to limit the movement of the latter in the body, said pin having its pointed end extending below the housing 65 when the latter is pendently supported, and means in connection with said stop to pendently support the housing, whereby initial contact of the pin with a subjacent surface is permitted.

6. A plumb bob, including a body, a cap for said body, a pin freely movable through said cap and body, said pin capable of being moved externally of either end of said cap and body, and means within said body for 75 limiting the movement of said pin.

7. A plumb bob, including a body having a threaded annular recess therein, a pin pro- 80 vided with a slot, and freely movable through said body, means passing through said slot for limiting the movement of said pin, and a cap screwed into said recess and abutting said means, said cap having an opening therein to permit of movement of said pin externally thereof.

8. A plumb bob, including a body having a central bore and a recess formed adjacent one end of said bore, a pin freely recipro- 90 cable within said bore and having a slotted upper portion, said pin being further pro- 95 vided with an enlarged head, said head hav- ing a convex surface and a central opening passing therethrough for communication with said slotted portion, a cap embracing said pin and fitted into said recess, and means passing through the slotted portion of said pin for limiting the movement of the latter, said means engaged between said cap and the base of said recess, whereby dis- placement from said recess is prevented.

In testimony whereof I affix my signature 100 in presence of two witnesses.

OBBO B. BERG.
